UNITED STATES PATENT OFFICE.

FRANZ KAULFERSCH, OF BAUTZEN, GERMANY.

MACHINE FOR FORMING AND FASTENING RIVETS OR CLAMPS.

SPECIFICATION forming part of Letters Patent No. 681,709, dated September 3, 1901.

Application filed December 10, 1900. Serial No. 39,430. (No model.)

To all whom it may concern:

Be it known that I, FRANZ KAULFERSCH, a subject of the Emperor of Austria-Hungary, residing at Bautzen, Kingdom of Saxony, 5 Germany, have invented a certain new and Improved Machine for Forming and Fastening Rivets or Clamps, of which the following is a full, clear, and exact description.

The present invention consists of a machine 10 for forming and fastening rivets or clamps, and relates more especially to the class of machines used in connection with the making of pasteboard boxes and the like.

The invention comprises the details of construction hereinafter set forth, and particularly pointed out in the claims.

In order to render the present specification easily intelligible, reference is had to the accompanying drawings, in which similar letters 20 of reference denote similar parts throughout the several views.

Figure 1 is a side elevation of the machine; Fig. 2, a front elevation; Fig. 3, an enlarged part section of the stamp and metal-feed device; Fig. 4, a part elevation showing the means for rotating the die; Fig. 5, a front elevation of the same parts. Figs. 6 and 7 are vertical sections through the double die, showing the position of the stamps in making and inserting the rivets. Fig. 8 is a plan of the metal strip from which the rivets are cut, and Fig. 9 is an enlarged view showing the rivets in position in the pasteboard.

The machine is driven by means of the belt-pulley *a* from a suitable source of power, and a coupling is interposed, actuated by a foot-lever *a'* and lever system *a''*, so that when the treadle *a'* is depressed by the operator the coupling (which may be of any suitable class) 35 will be disengaged and the belt-pulley will run without working the machine. On the pulley-shaft a crank-disk *b* is mounted, connected by means of a rod *c* with one end of a double lever *d*, pivotally mounted in the 40 machine-frame and having its free end coupled to the vertically-reciprocating stamp *e*. Toward the lower end this stamp is provided with a shoulder, and it is adapted to move in a sleeve *f*, which is also mounted to recip- 45 roate vertically in the machine-frame, being adapted to follow the downward movement of the stamp *e* to a certain extent. For this

purpose it is normally depressed by means of the two springs *u*, which hold the said sleeve against the shoulder of the stamp *e*, Fig. 3. 55 The sleeve *f* carries the die at its lower end, the said die being pivotally mounted in the sleeve and having two conical orifices therein, which are tapered in opposite directions. The strip of metal *B* is advantageously of the form 60 shown in Fig. 8, so that each piece cut off the same will be in the proper shape for a rivet or clamp. This strip is guided in a guide *l*, which is vertically movable in the machine-frame with the sleeve *f*, as hereinafter explained. 65

The stamp *e* is provided with a cutter *k* and with two stamps *e'* and *e''*, one of which is shorter than the other. The said stamps fit into the two conical orifices of the die. At 70 the descent of the stamps the shorter one *e''* enters the orifice *i* of the die and forms the rivet therein, Fig. 7, while the longer one *e'* forces the rivet or clamp previously formed down through the orifice *i'* into the paste- 75 board lying underneath the same on the anvil *A*. The rotary die *g* is mounted on the pivot-spindle *n*, and each time the stamp rises it is turned over, so as to bring the orifice containing the rivet *N* into position under the 80 longer of the two stamps *e*—*id est*, from the position shown at Fig. 6 to that in Fig. 7. Thus at each descent of the stamp one rivet or clamp will be formed in the orifice *i* by the stamp *e''* and the rivet formed by the pre- 85

vious descent will be driven into the pasteboard or other material by the stamp *e'*, the die having been turned over in the meantime by the following mechanism: Fast on the spindle *n* of the die *g* is a pinion *o*, which engages with a gear *p*, mounted on a stub-shaft *r*, fixed in the movable part of the machine—advantageously the sleeve *f*. Rigidly fixed to the gear *p* is a ratchet-wheel *q*, and a detent-pawl *w* prevents the same from being 90 turned back. A disk *s* is loosely mounted on the spindle *r* and carries a spring-pressed pawl *v*, which engages in the said ratchet-wheel *q*. This disk is linked to an arm *t*, pivotally suspended on a stationary part of the 95 machine. A spring-pressed finger *m* rests on the strip of metal *B*. The operation of this part of the machine takes place in the following manner: When the stamp *e* descends, the

sleeve *f* will be forced down with it by the springs *u* until the die *g* rests on the paste-board lying on the anvil *A*. Then the stamps *e* and *e*² continue their downward movement 5 and enter the orifices of the die *g*, making and fastening the rivets, as previously explained. After this has taken place the stamps rise again until the shoulder of the stamp *e* lifts the sleeve *f* against the action of its 10 springs. The metal-strip guide rises with the sleeve and passes up the metal strip, which is held by the finger, so that the end of the said strip will be projected out of the guide under the stamp *e*², Fig. 6. As the sleeve *f* rises the arm *t* partially rotates the disk *s*, and this disk rotates the ratchet-wheel *q*. This movement of the ratchet-wheel is transmitted to the pinion *n* of the die *g*, which is accordingly turned over, as will be readily 15 understood. The metal band is mounted on a spool *y*, revolvably mounted at *z* in the upper part of the machine-frame. The band is taken down with the guide when the latter sinks by means of the spring-pressed finger 20 *m*, or, more correctly, this finger prevents the band from rising with the guide.

I claim as my invention—

1. In a rivet or clamp forming and clamping machine, the combination of a vertically- 30 reciprocating double stamp, a rotary die having double orifice, and means for feeding a metal strip to one of the said orifices, means for differentially vertically reciprocating the said stamp and die and means for turning 35 over the said die at each reciprocation so as to reverse the position of the die-orifices as regards the double stamp, substantially as described.

2. In a clamp forming and fastening machine, the combination of a double stamp having a longer and a shorter member, a sleeve inclosing said stamp and a die having double 40

orifice pivotally mounted in the lower end of said sleeve, means for differentially reciprocating the said stamp and sleeve, a reciprocating guide for the metal strip and means for moving it on the metal strip when the stamp is raised and for taking it with the guide as the latter is depressed, a cutter on the stamp and means for reversing the position of the die-orifices as regards the two members of the double stamp when the said die is raised substantially as described. 45

3. In a clamp forming and riveting machine the combination of a double stamp, having a longer and a shorter member, a sleeve inclosing said stamp and having a die pivotally mounted in its lower end, a double orifice to said die to correspond with the two members of the stamp, means for feeding a strip of metal to the said die, a cutter on the stamp, a pinion on the die-spindle, a gear mounted on the said sleeve-and-ratchet mechanism in engagement with said gear, and means for operating said ratchet mechanism at each upward stroke of the sleeve to turn the gear a part of a revolution, and means for differentially reciprocating the said stamp and die sleeve substantially as described. 50

4. In a machine for forming and fastening 55 clamps, the combination of a double stamp and a pivotally-supported die having two orifices to correspond with the position of the two members of the stamp, means for differentially reciprocating the said die and stamp 60 and means for turning over the said die at each reciprocation in the manner and for the purpose substantially as described. 65

In witness whereof I have hereunto set my hand in presence of two witnesses.

FRANZ KAULFERSCHI.
